DELAWARE

HEAT EXCHANGER

Application filed December 10, 1931. Serial No. 580,072.

This invention relates to heat exchangers of the type in which a plurality of tubes are placed in a containing shell and which are commonly known as shell-and-tube or surface type heat exchangers.

5 This type of heat exchanger is used principally in transferring heat between two liquids, such as in oil refining operations and the like, and in transferring heat between a liquid and a gas as for example, in steam power plants and industrial establishments. When used for transferring heat between two liquids, one liquid is passed through the shell of the exchanger and comes in contact with the outside surfaces of the tubes and the other liquid is passed through the tubes and the transfer of heat between the liquids takes place through the walls of the tubes. In transferring heat between a liquid and gas 10 or vapor, the gas or vapor is usually passed into the shell and the liquid forced through the tubes.

In the particular form of shell-and-tube or surface type of heat exchanger with which 15 this invention is concerned, the tube bundle is secured at each end in a tube sheet and means are provided within the shell containing the tube bundle for conducting the fluid so that it makes two or more passes through 20 the tube bundle before being discharged.

Inasmuch as the tubes are usually made of a different metal than the shell and normally operate at a temperature different from that of the shell, the relative thermal 25 expansion between the tubes and the shell must be compensated for. To this end, one end of the tube bundle is anchored at its tube sheet to the shell, while the other end of the tube bundle and its tube sheet is supported so as to allow it to move bodily within the shell in response to thermal expansion or contraction of the tubes relatively to the shell and vice versa.

This floating tube sheet carries a cap 30 which forms with the tube sheet a sealed chamber at the end of the tube bundle for receiving the circulating fluid discharged from one portion of the tubes and redirecting it into another portion of the tubes. This cap moves with the floating tube sheet and

the entire organization at that end of the tube bundle is known as the floating head. Also, the tube bundle is of a diameter sufficiently small to permit ready removal of the entire tube bundle as a unit, including 35 the tubes and both tube sheets, for purposes of repair and periodic cleaning, especially when oil and other viscous liquids are used therein.

In order to effectively seal the connection 40 between the floating tube sheet and the cap of the floating head, a very tight joint between them must be provided. It has been common practice heretofore to employ clamping devices which hold the cap and the floating tube sheet securely together and yet may be released readily to enable the heat exchanger to be readily disassembled for cleaning and removing and replacing tubes and the like. These clamping means usually 45 include various kinds of so-called sectional rings to enable ready disassembling of the floating head and these have been found to be generally satisfactory except that the sectional clamping rings have a tendency to cock, rotate, or cant about the inner periphery of the tube sheet, which they are intended to clamp 50 squarely and securely to the cap, when the clamping means, such as bolts, are tightened down.

It is the principal object of this invention to provide a heat exchanger in which the floating head is so constructed that canting or cocking of the clamping rings is prevented or reduced to an unobjectionable degree, without sacrificing the ready assembling and disassembling of the floating head, which is so necessary to secure easy access to the parts 55 of the heat exchanger for cleaning and repair purposes.

In accordance with this object the heat exchanger includes a tube bundle having tube sheets at each end, one tube sheet being anchored to the shell in the usual way and the other tube sheet being arranged to float in the shell to accommodate relative thermal expansion between the tubes and the shell. The cap, into which one portion of the tubes discharge and which redirects the fluid into 60 another portion of the tubes, engages the 65

outer face of the floating tube sheet and the floating tube sheet is held against the cap in clamping relation by a sectional ring which embraces the peripheries of the cap and the floating tube sheet in the manner of a circular clamp. Suitable securing means on the sectional ring lock it to the floating tube sheet and cap and draw their edges together in snug and leak-proof cooperation. These securing means preferably comprise large set screws or bolts, which are threaded through the sectional ring and engage the cap at spaced intervals around its outer face adjacent its edge. The inner edge of the sectional ring is reversely turned and is seated in a groove in the inner face of the floating tube sheet. Instead of employing a split sectional ring of the form described, a segmental clamping ring or separate clamps, one for each set screw or bolt, may be employed.

With this construction, the parts of the sectional ring are securely held together by its connections with the outer face of the cap and the inner face of the floating tube sheet, and these connections brace the sectional ring segments, or separate clamps, against movement in all directions, so that cocking or canting of the inner edge thereof about the inner edge of the outer periphery of the floating tube sheet is effectively prevented and the cap and the tube sheet are clamped squarely and securely together. This construction, however, permits ready removal of the cap from the floating tube by simply loosening the set screws from the cap sufficiently to permit withdrawal of the reversely turned inner or opposite edge of the sectional ring parts or the corresponding segment or separate clamp from the groove on the inner face of the tube sheet, and then lifting these elements from their embracing engagement with the cap and tube sheet. The tube bundle including the floating sheet, is of such dimension as to permit ready withdrawal thereof as a unit from the shell for repairing and cleaning purposes.

For a better understanding of the invention, reference is made to the accompanying drawing, in which

Figure 1 is a longitudinal section of a heat exchanger embodying the construction of the present invention;

Fig. 2 is an expanded view of the floating head, consisting of the floating tube sheet secured to one end of the tube bundle, the cap, and the clamping means;

Fig. 3 is a reduced section through the modified or segmental clamping ring;

Fig. 4 is a face view of one of the clamping segments;

Fig. 5 is an edge view of a single clamp form of clamping means; and

Fig. 6 is an inside view thereof.

In the drawing, the heat exchanger includes the longitudinal cylindrical shell 10

having the inlet 11 at one side and the outlet 12 at the opposite side, whereby a fluid such as steam, water, oil, or the like, may be circulated through the shell. Supported within the shell 10 is a tube bundle 13 made up preferably of a relatively large number of small thin walled tubes. These tubes are expanded at the right-hand end into a fixed tube sheet 14 and at the left-hand end into a movable or floating tube sheet 15. In order to cause the liquid entering at the inlet 11 to pass longitudinally of the shell 10 and the tube bundle 13, a baffle plate 16 extends from the fixed tube sheet 14 centrally of the shell 10 and terminates at a point near the opposite end thereof.

The other fluid, such as oil for example, enters at the right-hand end of the exchanger through the inlet 17, which delivers it to a chamber 18 from which it flows into the tubes of the tube bundle 13 lying on the upper side of the dividing partition 19. The liquid passes through these tubes and is discharged into the floating chamber 20 at the left-hand end of the exchanger, which is formed between the cap 21 and the floating tube sheet 15, to which it is secured in a manner to be described. This chamber redirects the fluid into the tubes of the lower portion of the tube bundle 13, whereby the liquid is returned to the right-hand end of the exchanger and discharged into a chamber 22 on the lower side of the partition 19, from which it passes out of the outlet 23.

The shell 10 is provided at its right-hand end with a connecting flange 24 and at its left-hand end with a similar connecting flange 25. The fixed tube sheet 14 is clamped rigidly between the flange 24 and the castings 26 containing the inlet 17 and the outlet 23, by means of a plurality of long bolts 27. The shell 10 is closed at its left-hand end by means of a large dome-like cover 28, which is secured to connecting flange 25 by means of bolts 29. The liquid passing through the shell 10 is free to circulate within the dome-like cover 28 around the floating head of the tube bundle formed by the cap 21 and the floating tube plate 15.

This floating head is supported centrally in the dome-like cover 28 and the tube bundle 13 is supported centrally in the shell 10 by means of an annular disc 30 mounted on the tube bundle 13 near the left-hand end of the exchanger. This disc has a large central opening for the free passage of the fluid in the shell and is slidable axially in the shell 10 in response to the relative thermal expansion between the tube bundle 13 and the shell 10 and remaining stationary parts of the exchanger. This relative thermal expansion between the tube bundle 13 and the shell 10 and remaining parts of the exchanger takes place for the reason that the tubes 13 and the shell 10, being made of different materials have

different co-efficient of expansion. Also, the temperatures to which the shell 10 and the tubes 13 are subjected are frequently widely different so that the relative expansion of each varies considerably. The floating tube sheet 15 is of slightly smaller diameter than the inside diameter of shell 10 so that it can be withdrawn from the shell 10 in removing the tube bundle.

10 Cap 21 is provided with a thickened rim 31 and the inner edge of this rim is seated in a peripheral recess 32 formed in the outer surface of tube sheet 15. The opposite or inner face of tube sheet 15 is provided with an annular slot or groove 33. Encircling the peripheries of cap rim 31 and floating tube sheet 15 is a sectional or split ring 34, whose inner edge is provided with the radial flange 35 and whose outer edge is provided with the 20 radial flange 36, flanges 35 and 36 making the sectional ring 34 of generally channel or inverted U-shaped cross-section.

25 The inner flange 35 of the sectional or split ring 34 is provided with a reversely turned lip, rim or projection 37, which is adapted to fit into the angular groove 33 of the inner face of floating tube sheet 15, as shown especially in Fig. 1. When the two parts of the 30 sectional or split ring 34 are placed around the peripheries of cap rim 31 and floating tube sheet 15, the flange 35 overlaps the inner face of floating tube sheet 15 and the flange 36 overlaps the outer face of cap rim 31, so that the channel or U-shaped sectional or 35 split ring 34 spans or embraces the floating tube sheet 15 and cap rim 31, preferably around their entire peripheries.

30 Threaded through the outer flange 36 of the sectional or split ring 34 is a series of 40 equally spaced set screws or set bolts 38, whose tips bear against the outer surface of the cap rim 31 when the set screws or set bolts 38 are tightened down.

45 It will be seen that when the sectional or split ring 34 is emplaced on the floating head in the manner described, this ring is held on one side against radial spreading by the interlocking cooperation of lip, rim or projection 37 with the groove 33 on the inner face of floating tube sheet 15, and that the outer side of the sectional or split ring 34 is likewise kept from spreading radially by the spaced set screws or set bolts 38. It will also be seen that when the set screws or set bolts 38 are 50 tightened down, the peripheries of the floating tube sheet 15 and the cap rim 31, which cooperates with the recess 32 of the former, are drawn squarely and tightly together against movement in all directions. Also, 60 the sectional or split ring 34 is prevented from rocking, cocking or canting about the inner edge of the outer periphery of floating tube sheet 15, since the tips of set screws 38 hold it against any radial movement, such as 65 any tendency to rock, cock or cant.

In assembling the floating head of the heat exchanger, the inner edge of rim 31 of cap 21 is placed in the recess 32 of the floating tube sheet 15 and the two halves or parts of sectional ring 34 are placed around the peripheries of the abutting cap rim 31 and tube sheet 70

15, this sectional or split ring spanning or embracing the edges of the cap rim 31 and floating tube sheet 15 in the manner illustrated in Fig. 1, the lip, rim or projection 37 of inner flange 35 thereof resting in the groove 32 in the inner face of floating tube sheet 15. It is then only necessary to tighten down the set screws 38 in order to hold the halves of the sectional ring 34 together and draw the cap 21 and floating tube sheet 15 securely and squarely together to form a tight and leak-proof joint. In disassembling the floating head after removing the dome-like cover 28 of the exchanger, it is only necessary to loosen the set screws 38 to remove the two halves of the sectional ring 34 and thereafter the cap 21. The floating tube sheet 15, being of slightly smaller diameter than the inner diameter of the shell 10, may be drawn rapidly through the shell 10 if it is desired to abstract the tube bundle 13.

25 Instead of employing the sectional ring 34, a plurality of segmental clamps 39 may be substituted, each of these segments having 95

one or more and preferably two of the set screws or bolts 38' and cooperating end to end to form the complete ring 34' shown in Fig. 3. The single segment is shown in Fig. 4. This segmental clamping arrangement has all of the advantages of the sectional ring 34 described in connection with Figs. 1 and 2, and has the additional advantage of being easier to handle because of the smaller elements which make up the complete ring. 100

30 Another modified form of the clamping means is illustrated in Figs. 5 and 6. In this arrangement separate clamps 40, one for each set screw or bolt 38'' and having the same cross sectional shape as the sectional ring 34 and the segments 34', are spaced equi-distantly around the periphery of the cap rim 31 and floating tube sheet 15 to clamp them squarely and securely together in the manner described in connection with the arrangements of Figs. 1 to 4, inclusive. These separate clamps 40 have all the advantages of the arrangements of Figs. 1 to 4, inclusive, and have the additional advantages of lightness and easy handling. 110

35 Although the invention has been described in connection with a two-pass heat exchanger, it is to be understood that the invention is applicable with equal facility to a single pass heat exchanger or other apparatus requiring a tightly sealed connection of this type. 115

40 I claim:

45 1. In a heat exchanger, the combination of a shell, a tube bundle therein, a tube sheet for 120

125

130

one end of the tube bundle, a cap for said tube sheet having a rim engaging the outer face of the tube sheet, an element embracing the peripheries of the tube sheet and cap rim, and 5 means for securing the element in this position.

2. In a heat exchanger, the combination of a shell, a tube bundle therein, a tube sheet for one end of the tube bundle, a cap for said tube sheet having a rim engaging the outer face of the tube sheet, and an element engaging the inner face of the tube sheet and the outer face of the cap rim for holding the tube sheet and cap together. 10

3. In a heat exchanger, the combination of a shell, a tube bundle therein, a tube sheet for one end of the tube bundle, a cap for said tube sheet having a rim engaging the outer face of the tube sheet, an element engaging the inner face of the tube sheet and the outer face of the cap rim, and securing means on the element and engaging the cap for locking the tube sheet and cap together. 20

4. In a heat exchanger, the combination of a shell, a tube bundle therein, a tube sheet for one end of the tube bundle, a cap for said tube sheet having a rim engaging the outer face of the tube sheet, and an element spanning the peripheries of the tube sheet and cap rim and 30 engaging their opposite faces for clamping them together.

5. In a heat exchanger, the combination of a shell, a tube bundle therein, a tube sheet for one end of the tube bundle, a cap for said tube sheet having a rim engaging the outer face of the tube sheet, and an element spanning the peripheries of the tube sheet and cap rim, and means locking the element to the opposite faces of the tube sheet and cap rim. 35

6. In a heat exchanger, the combination of a shell, a tube bundle therein, a tube sheet for one end of the tube bundle, a cap for said tube sheet having a rim engaging the outer face of the tube sheet, and a clamping element of channel cross-section encircling the tube sheet and cap, the flanges of the element extending radially inwardly to overlap the opposite faces of the tube sheet and cap for locking them together. 40

7. In a heat exchanger, the combination of a shell, a tube bundle therein, a tube sheet for one end of the tube bundle, a cap for said tube sheet having a rim engaging the outer face of the tube sheet, an element of channel cross-section embracing the peripheries of the tube sheet and a cap rim, and means on the flanges of the element engaging the corresponding faces of the tube sheet and cap rim for clamping them together. 55

8. In a heat exchanger, the combination of a shell, a tube bundle therein, a tube sheet for one end of the tube bundle, a cap for said tube sheet having a rim engaging the outer face of the tube sheet, and a ring of channel cross-section placed jointly over the peripheries of the tube sheet and cap rim and secured thereto. 60

9. In a heat exchanger, the combination of a shell, a tube bundle therein, a tube sheet for one end of the tube bundle, a cap for said tube sheet having a rim engaging the outer face of the tube sheet, said tube sheet having a groove in its inner face, an element embracing the tube sheet and cap rim and having means projecting into the groove of the tube sheet, and means on the element engaging the outer face of the cap. 70

10. In a heat exchanger, the combination of a shell, a tube bundle therein, a tube sheet for one end of the tube bundle, a cap for said tube sheet having a rim engaging the outer face of the tube sheet, said tube sheet having a groove in its inner face, an element embracing the tube sheet and cap rim, a reversely turned flange on the element engaging the groove of the tube sheet and a radial flange on the element engaging the outer face of the cap. 80

11. In a heat exchanger, the combination of a shell, a tube bundle therein, a tube sheet for one end of the tube bundle, a cap for said tube sheet having a rim engaging the outer face of the tube sheet, said tube sheet having a groove in its inner face, an element embracing the tube sheet and cap rim, a reversely turned flange on the element engaging the groove of the tube sheet, a radial flange on the element overlapping the outer face of the cap, and set screws threaded through the radial flange of the element and engaging the cap rim for drawing the tube sheet and cap together. 90

12. In a heat exchanger, the combination of a shell, a tube bundle therein, a tube sheet for one end of the tube bundle, a cap for said tube sheet having a rim engaging the outer face of the tube sheet, said tube sheet having a groove in its inner face, an element of channel cross-section placed over the peripheries of the tube sheet and rim cap, one radial flange of the element having an inwardly turned edge lying on the tube sheet groove, and a plurality of set screws threaded through the other radial flange of the element and engaging the outer face of the cap rim for drawing the outer peripheries of the tube sheet and cap rim together within the channel of the element. 110

13. In a heat exchanger, the combination of a shell, a tube bundle therein, a tube sheet for one end of the tube bundle, a cap for said tube sheet having a rim engaging the outer face of the tube sheet, and a complete ring embracing the peripheries of the tube sheet and cap rim for clamping them together. 120

14. In a heat exchanger, the combination of a shell, a tube bundle therein, a tube sheet for one end of the tube bundle, a cap for said tube sheet having a rim engaging the outer face of the tube sheet, and a plurality of seg- 125

ments embracing the peripheries of the tube sheet and cap rim for clamping them together, said segments jointly forming a complete ring.

- 5 15. In a heat exchanger, the combination of a shell, a tube bundle therein, a tube sheet for one end of the tube bundle, a cap for said tube sheet having a rim engaging the outer face of the tube sheet, and separate clamps
10 embracing the tube sheet and cap rim and spaced around the peripheries thereof.

In testimony whereof I affix my signature.
OSCAR W. HEIMBERGER.
